UNITED STATES PATENT OFFICE

WALTER MYERS, OF BRIDGEPORT, CONNECTICUT, ASSIGNOR TO THE SINGER MANUFACTURING COMPANY, OF ELIZABETH, NEW JERSEY, A CORPORATION OF NEW JERSEY

ZIGZAG-STITCH SEWING MACHINE

Application filed January 10, 1930. Serial No. 419,815.

This invention relates to improvements in zigzag-stitch sewing machines and has for its primary object to provide improved actuating mechanism for vibrating the reciprocating needle laterally and for maintaining loop-seizing relationship between the laterally-vibrating needle and a loop-taker which cooperates therewith in the formation of stitches.

A further object of the invention is to provide a loop-taker compensating mechanism which is particularly adapted for a sewing machine having a work-cylinder of small diameter, whereby tubular articles of small compass may be readily stitched.

Other and more specific objects of the invention will be apparent from the following description and claims.

A preferred embodiment of the invention has been designed more particularly for joining straw-braids by zigzag stitches, although it is obviously adapted to other uses. In the present instance, the machine frame includes a work-supporting horn or cylinder and a bracket-arm overhanging the work-cylinder. The endwise reciprocating needle-bar is journaled in a vibratory-frame in the bracket-arm head, which frame is connected by a link with a pitman having a strap embracing an actuating eccentric adjustably secured upon a shaft rotating at one half the speed of the needle-reciprocating shaft.

The needle-vibrating pitman has a reciprocating pivotal-support which, in the preferred embodiment of the invention, is afforded by a pivotal-connection between an extension-arm of said pitman and a rock-lever supported by the bracket-arm. This rock-lever has an adjustable connection with a second rock-lever imparting reciprocatory movements, longitudinally of the work-cylinder, to a bracket in which is journaled a loop-taker of the vertical-axis rotary-hook type. The resulting shifting movements of the loop-taker correspond in direction and extent with the lateral movements of the needle.

Carried by the reciprocating loop-taker bracket is an arm having a needle-throat movable in a suitably apertured throat-plate

fixed upon the work-cylinder, said arm being provided with means for restraining the lower-thread bobbin-case against rotation with the loop-taker in which said bobbin-case is journaled.

The loop-taker is rotated by gear-connections with a rotary, loop-taker actuating-shaft, the driving gear being splined upon said shaft and shifted longitudinally thereof to maintain driving relationship between the gears during the lateral movements of the loop-taker.

In the accompanying drawings, Fig. 1 is a longitudinal section, partly in front elevation, of a sewing machine containing a preferred embodiment of the present improvement. Fig. 2 is a bottom-plan view of the base and work-cylinder of the machine, a portion of the free end of the cylinder being in section. Fig. 3 is a sectional view of the work-cylinder substantially on the line 3—3 of Fig. 1. Fig. 4 is a sectional view of the bracket-arm of the machine, substantially on the line 4—4 of Fig. 1. Fig. 5 is a perspective view of the loop-taker and feeding mechanism, with the feed-bar and its controlling link in detached relationship. Fig. 6 comprises perspective views of the throat-plate and of the needle-throat arm.

Referring to the drawings, the present improvement is shown as embodied in a sewing machine having a base 1, from which projects laterally a work-cylinder 2. Rising from the work-cylinder is the hollow standard 3 of a tubular bracket-arm 4, overhanging the work-cylinder and terminating in a head 5.

Journaled in suitable bearings in the bracket-arm is a main actuating-shaft 6, having the usual crank-disk 7 connected by means of a link 8 with a needle-bar 9 to impart endwise reciprocations thereto. The needle-bar 9, which at its lower end carries a needle 10, reciprocates in suitable bearings provided in a vibratory-frame 11 supported at its upper end by a pivot-pin 12 in the bracket-arm head 5.

Adjacent its free end, the frame 11 is pivotally connected by a stud 13 with one end of a link 14, of which the opposite end is connected by a taper-headed screw-bolt 15

with one arm 16 of a two-armed pitman 16, 17. Intermediate its ends, said pitman has a split hub or strap 18 embracing an actuating-eccentric 19, which extends laterally from an eccentric-frame 20. The eccentric-frame 20 is pivotally supported by a screw-bolt 21 upon a disk 22 having a hub 23 secured by a screw 24 upon a cross-shaft 25. This cross-shaft 25 is journaled in suitable bearings provided in the bracket-arm 4 so as to be disposed under and transversely of the main-shaft 6, said cross-shaft 25 carrying a worm-wheel 26 driven by a main-shaft worm-gear 27 at one half the speed of said main-shaft. In order to adjust the actuating-eccentric 19 with respect to the cross-shaft 25 and thereby change the degree of the effective or endwise movement of the pitman 16, 17, there is provided an adjusting rod 28 threaded into a longitudinal bore of the cross-shaft 25 and having a knurled-head 29. The tapered end 30 of the rod 28 engages the rounded end of a screw 31 adjustably threaded into the eccentric-frame 20 and entering a suitable aperture in the cross-shaft 25. Opposed to the screw 31 is a plunger 32 bearing against the shaft under the action of a spring 33 disposed in a socket in the frame 20. The pressure of the spring 33 may be regulated by means of a screw 34. The described eccentric-supporting and -adjusting means is constructed substantially in accordance with the disclosure in the patent to C. F. Gray, No. 1,020,089, Mar. 12, 1912.

The arm 17 of the two-armed pitman is connected by a taper-headed pivot-bolt 35 with an arm 36 of a rock-lever 36, 37 having intermediate its ends a hub 38 fulcrumed between two collars 39 upon a horizontally disposed bar 40 mounted in apertures in the front and rear walls of the bracket-arm, said bar 40 being substantially parallel with the cross-shaft 25. The free end of the arm 37 of said rock-lever 36, 37, has a threaded aperture adjustably receiving a ball-headed screw 41, fixed therein by a check-nut 42. A ball 43 at one end of the screw 41 is slidably fitted into an elongated ball-aperture 44 provided in the split upper end of an arm 45 of a second rock-lever 45, 46. A clamp-screw 47 is preferably employed for adjusting the size of the ball-aperture 44. It is evident that the described connection provides for slightly changing the throw of the arm 45 with respect to that of the lever-arm 37.

The rock-lever 45, 46 is fulcrumed upon a bar 48 supported by the bracket-arm standard 3 similarly to and substantially parallel with the bar 40. Upon the flattened lower end of the arm 46 is suitably secured one end of a flat-spring 49 of which the other end is suitably fixed upon an endwise-reciprocatory bar 50, said spring 49 constituting a yielding connection between the arcuately movable lever-arm 46 and the right-line reciprocating bar 50. The bar 50 is journaled in alined bearing-apertures provided within the work-cylinder 2 and has a reduced end 51 secured by a pin 52 in a suitably apertured loop-taker bracket 53. As shown more particularly in Figs. 3 and 5 of the drawings, the bracket 53 has oppositely directed guide-fins, as 54, slidably engaging guide-ledges, as 55, projecting inwardly from the work-cylinder wall, whereby said bracket is restrained against angular movement about the axis of the bar 50.

Journaled in a suitable bearing provided in the bracket 53 is a vertically disposed shaft 56 carrying at its upper end a loop-taker 57. The loop-taker 57 is of the rotary-hook type 80 having a loop-seizing beak 58 adapted to seize thread-loops presented by the needle and cast said loops about a mass of under-thread contained within a bobbin-case 59, journaled as usual in the loop-taker. It will be observed that the loop-taker is located at the side of the needle-path opposite to that occupied by the free end of the work-cylinder and consequently the work-cylinder may terminate abruptly closely adjacent to said needle-path, a feature which is highly desirable for certain classes of work. Access to the loop-taker and the lower-thread bobbin is afforded by the usual slide-plate 60 upon the top of the work-cylinder. 90

At its lower end, the loop-taker shaft 56 carries a bevel-gear 61 in mesh with a similar gear 62 of twice the size of the gear 61, the driving-gear 62 being slidably secured by a spline 63 upon a loop-taker actuating shaft 64. The shaft 64 is journaled in bearings within the work-cylinder and carries a pulley 65 connected by a cleated-belt 66 with a pulley 67 upon the main-shaft 6. The bracket 53 carries a depending fork 68 straddling a groove 69 provided between the gear 62 and a collar 70 adjustably secured upon the gear hub, whereby said gear is caused to partake of the lateral movements of the loop-taker and is constrained to rotate with the actuating-shaft 64. 100

Fixed in a suitable aperture in the bracket 53, by a set-screw 71, is the supporting-bar 72 of an upwardly extending arm 73 having upon its upper end a small, rectangular block 74, constituting a needle-throat and having a needle-aperture 75. The needle-throat block 74 projects into a suitable slot 76 formed in a throat-plate 77, secured upon the work-cylinder 2 and having a feed-dog slot 78. The throat-plate slot 76 affords sufficient clearance to provide for the lateral movements of the needle-throat block 74 with the loop-taker. 110

The inner face 79 of the arm 73 is partly cut away to provide an overhanging ledge 80 below which said arm-face 79 has a needle-groove 81 in alinement with the needle-throat aperture 75. The needle-groove 81 serves the 120

dual purpose of guiding the needle and insuring the formation of the needle-thread loops upon the loop-taker side of the needle. Projecting from the ledge 80 are spaced lugs, as 5 82, forming between them a stop-notch entered by the stop-lug 83 upon the lower-thread bobbin-case 59. Consequently, the bobbin-case rotation restraining means occupies a predetermined relationship with respect to the bobbin-case regardless of the lateral movements of the loop-taker in which the bobbin-case is journaled. Means, of a well known character, are employed, for providing a free thread-loop passage past the bobbin-case rotation restraining elements. This 10 opener-mechanism includes the eccentric-actuated opener-finger 84 which intermittently engages an ear 85 projecting from the bobbin-case.

15 The work-advancing mechanism comprises a feed-dog 86 vertically adjustable upon a feed-bar 87 having a hub 88 embracing a main feed-eccentric 89 upon the loop-taker actuating shaft 64. Projecting laterally 20 from the feed-bar is a pin 90 pivotally embraced by an apertured end of a link 91, of which the opposite end is similarly connected with a crank-arm 92 upon a feed rock-shaft 93. The rock-shaft 93 is journaled in 25 suitable bearings in the work-cylinder 2 and at its rearward end carries a crank-arm 94 connected by a pitman 95 with an auxiliary feed-eccentric 96 upon the main-shaft 6. The auxiliary-eccentric 96, in the present instance, is constructed substantially in accordance with the disclosure in the patent to W. F. Dial et al., No. 718,988, Jan. 27, 1903, and is 30 therefore adjustable to change the degree of rocking movement imparted to the rock-shaft 93. By adjusting the auxiliary-eccentric 96 into neutral position, the extent of feed motion is determined entirely by the action 35 of the eccentric 89 to rock the feed-bar 87 about its pivotal connection with the link 91. The effective work-feeding action of the eccentric 89 may, therefore, be increased or diminished by adjusting or retaining the auxiliary-eccentric 96 to actuate the feed rock-shaft 93 in properly timed relation with respect to the main rotating eccentric 89, as will 40 be self evident.

45 The free end of the work-cylinder 2 is closed by a cylindrical end-cap 97 slidingly fitted upon the cylinder for ready access to the operating mechanism enclosed thereby. Opposed to the feed-dog 86 is a presser-foot 98 which may be of any construction suitable to the work to be stitched.

50 It is believed that the operation of the machine is clearly understood from the foregoing description of the mechanism thereof. The endwise reciprocating needle 10 is laterally vibrated in a direction crosswise of the feed-direction and therefore effects the production of zigzag lock-stitches. The eccen-

tric-actuated two-armed pitman 16, 17, which imparts the lateral vibrations to the needle, likewise transmits bodily lateral movements to the vertical-axis loop-taker in a direction lengthwise of the work-cylinder, thereby 50 maintaining a predetermined loop-seizing relationship between the needle and loop-taker, regardless of the extent of lateral vibration of the needle.

Having thus set forth the nature of the 75 invention, what I claim herein is:

1. A sewing machine having a needle-bar, a vibratory-frame in which said needle-bar is journaled for endwise reciprocation, means for reciprocating said needle-bar, and means for imparting vibratory movements to said frame including a rotary actuating-eccentric, a pitman having a strap embracing said eccentric to derive circular movements therefrom, a reciprocating pivotal-support for 80 said pitman, and operative connections between the pitman and said frame.

2. A sewing machine having a needle-bar, a vibratory-frame in which said needle-bar is journaled for endwise reciprocation, means for imparting vibratory movements to said frame including a rotary actuating-eccentric, a pitman having a strap embracing said eccentric, a rock-arm, a pivotal support for the 85 pitman upon said rock-arm, and a link-connection between the pitman and said frame.

3. A sewing machine having a needle-bar, a vibratory-frame in which said needle-bar is journaled for endwise reciprocation, means for reciprocating said needle-bar, a rotary actuating-eccentric, a two-armed pitman having a strap between its ends embracing said actuating-eccentric, a reciprocating pivotal-support for one of the arms of said pitman, and a link-connection between the other pitman-arm and said frame for imparting lateral movements to said needle-bar.

4. A sewing machine having a needle-bar, a vibratory-frame in which said needle-bar is journaled for endwise reciprocation, a rotary needle-reciprocating shaft, a needle-bar vibrating shaft disposed transversely and rotating at one half the speed of the needle-reciprocating shaft, an eccentric adjustably carried by said needle-vibrating shaft, a two-armed pitman having a strap intermediate its ends embracing said eccentric, a reciprocating pivotal-support for one arm of said pitman, and an operative connection between the other arm of the pitman and said frame 110 for transmitting vibratory movements thereto.

5. A sewing machine having a needle-carrying bar, a loop-taker cooperating with the needle carried by said bar in the formation of stitches, a vibratory-frame in which the needle-bar is journaled for endwise reciprocation, means for reciprocating said needle-bar, a rotary actuating-eccentric, a pitman having a strap embracing said eccentric, a 120

link connecting the pitman with said vibratory frame, and means including a reciprocating pivotal-support for said pitman for transmitting the endwise movements of the pitman to said loop-taker to compensate for the lateral vibrations of the needle.

6. A sewing machine having a needle-carrying bar, a loop-taker cooperating with the needle carried by said bar in the formation 10 of stitches, a vibratory-frame in which the needle-bar is journaled for endwise reciprocation, means for reciprocating said needle-bar, a rotary actuating-eccentric, a two-armed pitman having a strap intermediate its 15 ends embracing said eccentric, operative connections between one arm of the pitman and said vibratory-frame for imparting lateral movements to the needle, and operative connections between the other arm of the pitman 20 and said loop-taker for imparting movements to the loop-taker compensating for the lateral movements of the needle.

7. A sewing machine having a needle-carrying bar, a loop-taker cooperating with 25 the needle carried by said bar in the formation of stitches, a vibratory-frame in which the needle-bar is journaled for endwise reciprocation, means for reciprocating said needle-bar, a rotary actuating eccentric, a 30 two-armed pitman having a strap intermediate its ends embracing said eccentric, a link connecting one arm of the pitman with said vibratory-frame, a rock-lever pivotally connected with the other arm of said pitman, and 35 connections with said rock-lever for transmitting bodily lateral movements to the loop-taker to compensate for the lateral vibrations of the needle.

8. In a sewing machine having a work-cylinder and a bracket-arm overhanging the work-cylinder, a needle-carrying bar, a vibratory-frame mounted in the bracket-arm in which the needle-bar is journaled for endwise reciprocation, means for reciprocating the 40 needle-bar, means for vibrating said frame, a vertical-axis rotary loop-taker cooperating with the needle in the formation of lock-stitches, a bobbin-case journaled in said loop-taker, a bracket movably supported by the 45 work-cylinder in which said loop-taker is journalized to seize needle-thread loops at the side of the needle opposite to the free end of the work-cylinder, a needle-throat carried by said bracket for reciprocation therewith, means carried by said bracket for restraining the bobbin-case against rotation with said 50 loop-taker, and means for reciprocating said bracket longitudinally of the work-cylinder in timed relation with the lateral vibrations 55 of the needle to maintain loop-seizing relationship between the needle and the loop-taker.

9. In a sewing machine having a work-cylinder and a bracket-arm overhanging the 60 work-cylinder, a needle-carrying bar, a vibra-

tory-frame mounted in the bracket-arm for swinging movements in the direction of the length of the work-cylinder, in which frame the needle-bar is journaled for endwise reciprocation, means for reciprocating the needle-bar, a rotary actuating eccentric journaled in said bracket-arm, a two-armed pitman having a strap intermediate its ends embracing said eccentric, operative connections between one arm of the pitman and said vibratory-frame, 70 a rock-lever pivotally connected with the other arm of said pitman, a second rock-lever, an extensible ball-joint connection between said rock-levers, a rotary loop-taker supported for reciprocation longitudinally of the 75 cylinder, means for rotating said loop-taker, and operative connections for reciprocating said loop-taker from said second rock-lever.

10. A sewing machine having a needle-carrying bar, a vibratory-frame in which the needle-bar is journaled for endwise reciprocation, means for reciprocating the needle-bar, means for laterally vibrating said frame, a vertical-axis rotary loop-taker cooperating 80 with the needle carried by said bar in the formation of lock-stitches, a bobbin-case journaled in said loop-taker, a bracket in which said loop-taker is journaled, means for rotating the loop-taker, means for reciprocating said bracket in timed relation with the needle-vibrations to maintain loop-seizing relation 85 between the needle and loop-taker, an arm having a needle-throat carried by the bracket for reciprocation therewith, and coating elements upon the needle-throat arm and the 90 bobbin-case for restraining said bobbin-case 95 against rotation with the loop-taker.

In testimony whereof, I have signed my name to this specification.

WALTER MYERS. 105
